TRANSPARENT UNBREAKABLE NONRE-
FILLABLE CONTAINERTheodore B. McGirr, New York, and Theodore G.
McGirr, Brooklyn, N. Y.

Application August 31, 1940, Serial No. 355,074

3 Claims. (Cl. 229—51)

Our invention relates to containers and more particularly to the class known as one trip or single use containers which are meant to be used but once and then to be thrown away. In accordance with our invention the container is especially constructed so as to prevent refilling and sale of the container with contents again.

One object of our invention lies in the provision of a container which may be formed from transparent material such as cellulose or similar material.

A further object herein is to provide a container that is capable of holding oil and like materials.

A further object is to provide a container which, while light in weight, has a high tensile strength.

A further object is to provide a single trip or one use container which, having been emptied will give visible notice that it has been previously used, should anyone attempt to refill it and offer it for sale.

A further object is to provide a container having a spout formed from the top of the container, after same has been opened, for guiding the flow of its contents, while the container is being emptied, and forming an integral part of the top of the container before it is severed from the container.

A further object is to provide a seamless container, wherein the contents are completely visible.

A still further object is to provide a container which may be manufactured and printed with suitable advertising matter as may be necessary to identify its contents, then a plurality of the printed containers may be nested, and shipped to the distributor where they are filled and have bottoms put in them, the bottoms then being welded to the cylinder wall, forming, in fact, a seamless container.

A further object is to provide a container which must be substantially destroyed to remove its contents.

In accordance with the present construction single use containers may be made in large quantities, at low cost, so that they may have a consequent wide use.

The invention comprises a novel construction and arrangement of parts hereinafter more specifically described and illustrated in the accompanying drawing which refers particularly to the exemplary embodiments of the invention. However, as many changes can be made in the above construction and many widely different embodi-

ments of this invention could be made, without departing from the scope thereof, it is intended that all matter contained in the description, drawing, and claims shall be interpreted as illustrative and not in a limited sense.

The objects set forth hereinabove and other incidental ends and advantages will more fully appear in the progress of this disclosure and be pointed out in the appended claims.

In the drawing forming a material part of this disclosure similar reference characters designating corresponding parts throughout the several views in which:

Figure 1 in the drawing is a fragmentary plan view of a first embodiment of the invention showing that portion or the top from which the spout is formed.

Figure 2 is a vertical sectional view of the container as seen from the plane A—A on Figure 1.

Figure 3 is a bottom plan view of the container of Figure 1 before the bottom is put in place.

Figure 4 is a sectional view as seen from the plane B—B on Figure 3.

Figure 5 is a fragmentary sectional view of a second form of container.

Figure 6 shows a handy means for severing the top of the trough to form the spout on the first embodiment.

Figure 7 shows a third form of the container wherein the top of the container is peaked but not conical, the top having one straight side, a continuation of the side wall of the container, which terminates in the front end wall of trough.

Figure 8 is a fragmentary sectional view of a fourth form of container.

The container we have invented to meet the objects stated above consists of a container having a cylindrical body, made from some transparent material, preferably cellulose acetate. This container may be fabricated and welded or formed from a slug or other mass of material deposited within a properly prepared mold.

The cylinder side wall 1 is slightly tapered toward the top 14 which is conical in shape and has an outwardly raised troughlike protrusion as shown in Figures 1, 2, 6. This troughlike protrusion has side walls 15 and a head 3 all of which are continuations of the shell of the conical top portion 14. The side walls 15 of the trough are provided with a score 2 near where it merges with the conical top 14, to permit easier severing of the upper portion thereof. The conical top may be provided with corrugations instead of being plain as shown in the drawing.

The side wall 1 is slightly tapered so as to permit the containers being nested, when being shipped to the distributors. The side wall 1 at its lower end has an outwardly projecting offset 4 and a lower skirt portion 5 which extends downwardly. This skirtlike extension 5 of the side wall 1 of the container is in excess to the length of the side wall 7 of the bottom 6. The bottom 6 has a downwardly extending side wall 7 therefrom and is crowned upwardly to withstand greater pressure and also for the same purpose are ribs 9 arranged radially on the bottom, which are formed out of the bottom as shown in Figures 3, 4.

When the containers are filled at the distributors they are filled bottom side up. After the milk, oil or other substance has been put into the container, the bottom 6 is put in place, seated on shoulder formed by offset 4 of the side wall 1 of the container. Then the skirt portion 5, which is in fact a continuation of the offset portion of the side wall 1 and which is in excess to the length of the side wall 7 of the bottom 6, is formed over and down or upwardly as viewed in Figure 2 on the skirt portion 7 of the bottom 6. When this has been done, suitable heat and pressure is applied and the three thicknesses of the side walls are actually welded into a single thickness, thereby eliminating any seam or joint between the bottom 6 and the side wall 1 of the container.

To remove the milk, oil or other contents from the container, any edged implement may be used to sever the upper portion of the trough, by merely inserting the implement into the scored portion 2 and cutting the top portion entirely off. When the upper portion of the trough has been severed, the portion which remains, forms a spout or funnel which guides the stream of contents as it flows from the container. This enables one to pour the contents into a small opening with certainty.

When the container is empty it may not be refilled because, due to the shape of the opening, it would be difficult to put a cover on it and even then it would give visible evidence that it had been previously opened. The side walls 15 may also be made to taper slightly towards the top to make more difficult the applying of a cover which in conjunction with the corrugated conical top would make it impossible to ever reseal it after it has been opened, as we have previously stated giving visible evidence that the container had been opened before. Thus when the upper portion is severed the container is substantially destroyed.

The fragmentary view 6 shows another way the top portion of the trough may be severed, consisting of two buttons 10, 11 around which is wound a wire or other cutting agent, 13 which has a tab 12 fastened to one end thereof. To remove the contents it is only necessary to place

the cutting agent 13 into the scored portion 2 around the trough and pull. Because the cutting agent 13 is anchored on the bottom 10 the pulling of the tab 12 will cause the upper portion of the trough to be cut off.

Figure 7 shows another modification of the container, in this view the apex of the peaked top is in line with the side wall of the container. The trough is formed out of the top and is also provided with a scored portion 2 which goes all around the trough. The top of the trough would be severed and the container destroyed in the manner previously described.

In Figure 5 a different form of container is shown. The cover 16 is provided with a score groove 17 which may be removed with any sharp implement. In Figure 8 a thin portion which may also be removed as is the cover shown in Figure 5.

We claim:

1. A container of the kind described of cellulose material including a body and an integral conical top having an apex, and providing a bend at the junction of the top and body, said conical top being normally closed from the bend to the apex and having a narrow hollow rib protruding outwardly from said top and extending downwardly from the apex of the cone to said bend whereby removal of the upper part of the rib along its length provides a narrow pouring slot.

2. A container of the kind described of cellulose material including a body and an integral conical top having an apex, and providing a bend at the junction of the top and body, said conical top being normally closed from the bend to the apex and having a narrow hollow rib protruding outwardly from said top and extending downwardly from the apex of the cone to said bend whereby removal of the upper part of the rib along its length provides a narrow pouring slot, said rib being provided with a peripherally extending groove forming a weakened guide line for a severing device.

3. A container of the kind described of cellulose material including a body and an integral conical top having an apex, and providing a bend at the junction of the top and body, said conical top being normally closed from the bend to the apex and having a narrow hollow rib protruding therefrom and extending downwardly from the apex of the cone to said bend whereby removal of the upper part of the rib along its length provides a narrow pouring slot, said rib being provided with a peripherally extending groove forming a weakened guide line for a severing device, and a severing strand having one end secured to the body adjacent the lower end of the rib and of a length adapted to pass around the rib.
